By his Attorneys,

Nathan Milam, Inventor

UNITED STATES PATENT OFFICE.

NATHAN MILAM, OF GREENSBOROUGH, NORTH CAROLINA.

HASP-FASTENER.

SPECIFICATION forming part of Letters Patent No. 657,434, dated September 4, 1900.

Application filed December 14, 1899. Serial No. 740,329. (No model.)

To all whom it may concern:

Be it known that I, NATHAN MILAM, a citizen of the United States, residing at Greensborough, in the county of Guilford and State of North Carolina, have invented a new and useful Hasp-Fastener, of which the following is a specification.

This invention relates to hasp-fasteners, and has for its object to provide improved means for automatically securing the hasp or locking member to the staple or keeper while the former is being engaged with the latter and which may be conveniently operated to release the hasp or locking member when it is desired to remove the latter from the keeper.

With these and other objects in view the present invention consists in the combination and arrangement of parts, as will be herein-after more fully described, shown in the accompanying drawings, and particularly pointed out in the appended claim, it being understood that changes in the form, proportion, size, and minor details may be made within the scope of the appended claim without departing from the spirit or sacrificing any of the advantages of the invention.

In the drawings, Figure 1 is a perspective view of a hasp-fastener constructed in accordance with the present invention. Fig. 2 is a transverse sectional view thereof. Fig. 3 is a detail perspective view of the gravity latch or detent.

Corresponding parts in the several figures of the drawings are designated by like characters of reference.

Referring to the accompanying drawings, 1 designates the locking member, which is shown in the form of a flat hasp, having its rear end connected to the door 2 by means of 40 a staple 3, so as to form a pivotal connection for the hasp. The opposite free end of the hasp overlaps the door-frame 4 at the free edge of the door and is provided with a longitudinally-disposed slot or eye 5. At the 45 free extremity of the hasp there is provided a transversely-disposed and outwardly-directed lug or shoulder 6, forming a thumb-piece for operating the hasp. Fitted to the door-frame 4 is the usual staple or keeper 7, which 50 is received through the slot or eye 5 in the common or ordinary manner. Instead of loosely connecting the hasp to the door the

former may be fixedly connected to the latter, as will be understood.

The foregoing-described parts may have 55 any common or preferred form, and in carrying out the present invention there is provided a gravity latch or detent 8, having an enlarged and weighted lower end 9 and an operating thumb-piece 10, located at the opposite 60 upper end of the detent and directed outwardly therefrom. Intermediate of the opposite ends of the detent and projecting rearwardly therefrom is a lug 11, provided with a central perforation 12, extending transversely 65 of the detent and forming a bearing-eye for pivotal connection with the hasp or locking member. In applying the detent to the hasp the latter is provided with a transverse slot 13, extending from the upper edge of the hasp 70 and communicating with the longitudinal slot or eye 5 at an intermediate point thereof and forming a substantially T-shaped slot. The bearing eye or lug 11 of the detent is loosely received within the entrance-slot 13 75 and pivotally mounted upon a pivot-pin 14, extending transversely of the slot and intermediate of the ends thereof, so that the detent is mounted to swing in a plane at substantially right angles to that of the hasp. 80 To facilitate the application of the latch or detent 8, the bearing-eye 11 is formed by means of a substantially U-shaped clip, which is fitted to the pivot-pin 14 from the rear side of the hasp, the opposite ends of the clip being received within perforations formed in the detent, and the extremities of the clip are afterward upset, so as to firmly connect the clip to the detent. As indicated in Fig. 2 of the drawings, it will be seen that the 90 gravity-detent 8 is located upon the outer side of the hasp and extends transversely across the slot or eye 5, the lower free extremity of the detent engaging against the outer side of the hasp, so as to prevent the 95 former from swinging into the slot.

During the application of the hasp to the keeper and while the latter is being received within the slot or eye 5 said keeper engages the rear side of the detent and forces the latter upwardly until it clears the upper side of the keeper and automatically drops into the latter. It will be seen that the hasp cannot be accidentally removed from the keeper, as

an outward movement of the hasp will engage the detent 7 against the inner side of the staple or keeper, thereby preventing entire disengagement of the hasp from the keeper. It is preferable to enlarge the lower free end of the detent, so that the latter may quickly gravitate into the keeper when the former becomes disengaged from the latter during the application of the hasp to the keeper. The staple or keeper 7 normally projects outwardly beyond the hasp at a suitable distance to permit of the detent being swung upwardly by means of the thumb-piece 10, so as to be situated above the staple, and thereby by permit of the disengagement of the hasp from the keeper.

15 What is claimed is—
In a hasp-fastener, the combination with a pivotal hasp, having a longitudinal slot, a
20 transverse entrance-slot communicating with

the longitudinal slot, and provided with a pivot-pin extending transversely across said transverse slot and supported by the opposite walls thereof, of a staple-shaped keeper to project through the longitudinal slot, and a 25 gravity-detent, having its lower end enlarged or weighted, and its upper end bowed outwardly to form a finger-piece, and a substantially U-shaped clip to pivotally embrace the pivot-pin, and having its opposite ends connected to the detent at a point intermediate of its ends.

25 In testimony that I claim the foregoing as my own I have hereto affixed my signature in the presence of two witnesses.

NATHAN MILAM.
